UNITED STATES PATENT OFFICE.

HENRY K. MULFORD, OF PHILADELPHIA, PENNSYLVANIA, ASSIGNOR TO NATIONAL DRUG CO., OF PHILADELPHIA, PENNSYLVANIA, A CORPORATION OF PENNSYLVANIA.

COMBINED STOPPER AND BULB SYRINGE.

Application filed February 15, 1927. Serial No. 168,280.

My invention relates to a new and useful combined stopper and bulb syringe, and more particularly to a syringe which is especially adapted for the injection of antiseptic and prophylactic and similar medicinal solutions into internal organs of the human body, as in the lavage of urethral and vaginal tracts and similar uses.

My invention further relates to a bulb 10 syringe of this character which will also serve as a stopper for the bottle or other receptacle containing the solution to be administered, thereby eliminating the need for a separate and independent closure for such 15 receptacle.

My invention further provides a novel combined stopper and bulb syringe, which will be sterile and sanitary at all times, thereby not only preventing any possible infection, but also rendering the same quickly 20 available for use at all times and eliminating the necessity of repeated sterilization and disinfection that would otherwise be necessary, whenever it is desired to use the 25 device.

My invention still further resides in the provision of a combined stopper and bulb syringe, in an integral, unitary structure, which occupies a minimum amount of space 30 in a medicine closet or emergency kit and the like, which is convenient for the patient to use, and which may be at all times instantly available for use thus insuring regularity of applying solutions for treatment, 35 and one which is less expensive to manufacture and distribute.

It has been the practice heretofore, to employ bulb syringes manufactured and sold independently of the receptacle containing 40 the solution to be injected. Obviously when such syringe was not in actual use, the same was ordinarily stored or kept in a container or closet, where the tube portion thereof, that is, the portion to be introduced into the 45 urethral or vaginal tract or other internal organ of the body, came in contact with air and other objects and was thereby contaminated. Thus, before such syringe was fit for use, it was necessary thoroughly to sterilize the same, all of which was not only 50 laborious and time consuming, but was often impossible or difficult of accomplishment, particularly if and when the same was being used by a layman without professional 55 aid. This practice further necessitated pur-

chase and keeping of a separate, additional article, which in addition to the cost of manufacture of the article, was not altogether convenient since the same occupied additional space and was always liable to be 60 mislaid, broken or lost.

It is the object of my invention to provide a syringe of this general character, which also serves as a stopper for the bottle or other receptacle in conjunction with 65 which it is to be used, to provide a syringe that will be sterile and sanitary at all times, thereby to eliminate the necessity of constant and repeated sterilization and to produce a more effective, compact and economical article. 70

To the above ends, my invention consists of a novel unitary, combined stopper and bulb syringe, comprising an upper substantially spherical, resilient, compressible portion having an air chamber formed therein, said spherical portion being constricted at the base thereof, and continued downwardly in a relatively thickened, conical tapering stopper or body portion adapted to fit snugly 80 in the mouth of a bottle and extend therewith, and having a passage extending through said stopper body or tapering conical portion and leading into said air chamber, the construction being such that the solution trickles or is injected slowly into the tract to be treated, thereby preventing the occurrence of spasms or inflammation of the 85 genital organs and enabling the solution to come in full contact with the area to be 90 treated.

My invention further consists of the combination with a bottle of a slightly modified construction of combined stopper and bulb syringe, in which I employ an elongated tubular extension detachably secured in the stopper body and extending into said bottle 95 said combined stopper and bulb syringe, and said elongated tubular extension, coacting as a unit and being readily insertible into or 100 withdrawn from said bottle.

For the purpose of illustrating my invention, I have shown, in the accompanying drawings, forms thereof which are at present preferred by me, since they will give in practice, satisfactory and reliable results, although it is to be understood that the various instrumentalities of which my invention consists can be variously arranged and organized and that my invention is not limited 110

to the precise arrangement and organization of these instrumentalities as herein shown and described.

Figure 1 represents a perspective view of a novel combined stopper and bulb syringe, embodying my invention.

Figure 2 represents a vertical sectional view of the same shown applied to a bottle, the latter being shown in dotted lines.

10 Figure 3 represents a perspective view of a modified construction of combined stopper and bulb syringe in detached position.

15 Figure 4 represents a vertical sectional view of the device seen in Figure 3 as applied to a bottle, the latter being shown in dotted lines, and the tube being shown in elevation.

20 Referring to the drawings in which like reference characters designate like parts, 1 designates my novel construction of a combined stopper and bulb syringe, comprising the thickened body portion 2, having the neck 2^x, merging into and terminating in the upper, resilient, hollow spherical or bulb portion 3, the interior of which forms the compression chamber 4. The thickened body portion 2 is continued downwardly to form the slightly conical portion 6 which is adapted tightly to fit in the mouth or neck of a 25 bottle 17, to prevent spilling, leakage or evaporation, as will be understood from Figure 2. The slightly conical portion 6 is continued downwardly, in a tapering conical portion 7, which merges into the pointed terminal 8. 5 designates a passage extending through the body portion 2 from the chamber 4 to the point 8, as will be understood from Figure 2.

30 Thus when it is desired to use my novel 10 combined stopper and bulb syringe, it is merely necessary to withdraw the conical portion 6 from engagement with the bottle neck, compress the bulb, and then immerse the end 8 in the solution contained in said bottle, with the resilient compressible or bulb portion 3 in its compressed or collapsed condition and finally to release the pressure on said bulb 3, whereupon, due to its inherent 35 resiliency, it will tend to resume its normal spherical shape, thereby drawing or sucking into the chamber 4, through the passage 5, the desired amount of the solution contained in the bottle 17. The solution can then be injected at any desired point in the usual manner.

40 In Figures 3 and 4, I have shown a modified construction of my novel combined stopper and bulb syringe, generally designated by the numeral 9 and comprising the bulged portion 10 within which is formed a horizontally disposed annular seat 10^x to receive the flange 11 on the upper end of a pendant extension tube 12, having the rounded or pointed end 13. 14 designates the resilient, 45 hollow, spherical or bulb portion, the interior

of which forms the compression chamber 15. 16 designates a lower conical tapering body portion adapted to fit tightly in the neck 70 of a bottle 17, as will be understood from Figure 4.

75 The operation, purpose and function of this modified construction are substantially the same as above set forth, except that by employing the extension tube 12, I facilitate the removal by suction of all of the contents of the bottle 17 without the necessity of tilting the latter, and provide a more effective syringe in cases where it is necessary to inject the solution some distance into internal organs, as is the case in the treatment of 80 urethral and vaginal infections.

85 It is to be understood that the extension tube 12 may be made of glass, hard or vulcanized rubber, metal or any other suitable material. The portions 3 and 14 may be of rubber or any other suitable material. The flange 11, when in the assembled position seen in Figure 4, will be tightly and frictionally held to its seat within the bulb 14, so that the tube 12 and the bulb 14 may be 90 manually manipulated as a unit and in both of the embodiments of my invention the compressible bulb and the bottle stopper or body portion are an integral, unitary structure, capable of performing the dual function of a syringe and a bottle closure as is evident.

95 It will further be understood that it is within the scope of my invention to elongate the conical portion 7 of the combined stopper and bulb syringe, shown particularly in Figures 1 and 2, to any desired extent.

100 Thus, after the syringe element has been used, the same is washed and replaced in position with respect to the bottle, (see 105 Figs. 2 and 4) where the tapering portion 7 or tube 12 thereof are protected against contamination and breakage and the syringe is thus ready for immediate use at all times.

110 It will be seen from the foregoing, that I have devised a new and useful combined stopper and bulb syringe which, in addition to being effective and sanitary, also occupies a minimum amount of space when not in use and can be manufactured at a minimum cost. It will also be apparent that the construction of my novel bulb syringe requires the 115 solution to trickle or be injected slowly—without much force—thereby preventing the spasm and undue irritation or inflammation of the infected organ being treated, which is a desirable function in devices of this character.

120 Having thus described my invention, what I claim as new and desire to secure by Letters Patent is:

125 1. A combined integral stopper and bulb syringe, comprising an upper, resilient, hollow portion, having a compression chamber formed therein and outwardly bulged at the 130

base thereof, so as to form a horizontally disposed internal integral seat, an integral pendant, conical body portion below said bulged portion and adapted tightly to fit in the mouth of a bottle as an integral stopper therefor, an extension tube having an upper flange positioned on said seat, within said integral bulged portion and extending downwardly into said bottle, and an upper, annular, internal, horizontal shoulder formed in said bulged portion above said seat to prevent the upward displacement of said extension tube.

2. The combination with a bottle of a combined integral stopper and bulb syringe, comprising an upper, resilient, hollow por-

tion having a compression chamber formed therein and outwardly bulged at the base thereof to form an annular integral internal seat, an integral, pendant, conical body portion adapted tightly to fit in the mouth of a bottle as an integral stopper to seal the same, an extension tube having an upper flange seated within said integral annular seat within said integral bulged portion and extending downwardly into said bottle, and an upper, annular, internal, horizontal shoulder formed in said bulged portion above said seat to prevent the upward displacement of said extension tube.

HENRY K. MULFORD.
